UNITED STATES PATENT OFFICE.

FRANK W. BROWN, OF BELDING, MICHIGAN.

ADJUSTABLE SAW-SETTING DEVICE.

1,217,697.

Specification of Letters Patent. Patented Feb. 27, 1917.

Application filed August 26, 1915. Serial No. 47,443.

To all whom it may concern:

Be it known that I, FRANK W. BROWN, a citizen of the United States, residing at Belding, in the county of Ionia, State of Michigan, have invented certain new and useful Improvements in Adjustable Saw-Setting Devices; and I do hereby declare the following to be a full, clear, and exact description of the invention, such as will enable others skilled in the art to which it appertains to make and use the same.

This invention relates to new and useful improvements in devices for setting saws and is particularly directed to the provision of such a device which is adapted for setting teeth of saws both of the cross cut type and of the type including hand or circular saws.

It is the object of the present invention to provide such a device wherein provision is made for adjusting both the degree of inclination and the length of the set imparted to the teeth, and it is more specifically an object to provide such a device wherein these adjusting means are associated therewith in an exceedingly simple manner conducive to economy in manufacture.

It is further an object to provide such a device wherein the various adjustments named may be made in a ready and easy manner.

With the above and other objects and advantages in view, the invention resides in the novel combination, formation and arrangement of parts as more fully described hereinafter and pointed out in the appended claims.

Reference is had to the accompanying drawings, wherein similar characters of reference designate corresponding parts throughout the several views, and in which:

Figure 1 is a side elevation of the improved saw setting device.

Fig. 2 is a vertical longitudinal sectional view therethrough.

Fig. 3 is a transverse sectional view on line 3—3 of Fig. 1.

Fig. 4 is a perspective view of one of the guides for regulating the depth of the set.

Referring now more particularly to the accompanying drawings, the improved device is shown as comprising a rectangular base member or body block 5 at the central portions of the sides of which are provided upstanding ears 6 between which are piv-

oted by means of the bolt 7 a bar 8 which has its ends enlarged to form setting heads 9 and 10, respectively, the head 9 being adapted to treat cross cut saws and having a squared end and having its bottom beveled as at 11 to contact with the upper surface of the tooth to be set. The head 10 is adapted to saws such as hand saws having triangular teeth, and has its end beveled at 12. Disposed on the under portions of the body bar are plates 13 which terminate short of the ears and have their portions under the head members beveled at 14 so that a saw may be placed on one of said plates and the respective head struck a light blow with a hammer to set the teeth. The heads are normally held in horizontal alinement by coil springs 15 disposed thereunder and having their ends engaged in sockets 16 in the head and adjacent portions of the body.

For adjusting the angular portion of the saw with relation to these plates 13 and to thus adjust the angle or degree of set imparted to the saw blade, a screw 18 is threaded vertically through each end of the block and through the outer ends of said plates, these bolts thus serving also as the securing means of the outer ends of the plates 13. The inner ends of the plates are held against lateral displacement on the body block and at the same time a securing means is provided for a suitable base block 20 for the device by means of bolts 21 which are passed through the block and threaded in the body and having their threaded ends threaded into bores 22 provided in the inner ends of the plates 13, the heads of these bolts 21 seating in a longitudinal groove in the bottom of the base block.

To provide a means for adjusting the depth of the set imparted to the saw teeth, a pair of guide arms 23 are provided for the side of each head portion 9 and the adjacent portion of the body 5 is provided with an elongated slot 24 through which and through the lower ends of the arms is passed a bolt 25 carrying at one end a wing nut 26 whereby the arms may be clamped against the body, the head of this bolt seating in a cutaway portion 27 in the lower end of the respective arm. The arms are held in upright position by square bosses 28 on their lower ends which project into recesses 29 formed in the sides of the body block adjacent the slots.

The heads 9 and 10 are slightly less in

width than the body block so that they may move freely between said arms.

A device has thus been provided which will efficiently perform the functions set forth and which is capable of full adjustment to meet various conditions, and which further has its parts so arranged and so co-acting as to form a structure of maximum simplicity.

10 The corners of the base block 20 are preferably provided with spike members 30 whereby the block may be securely fastened on any desired surface.

While I have illustrated and described 15 a particular embodiment of my invention, I have merely done so for the sake of convenience and I do not wish to be limited to that particular embodiment as it is obvious that numerous changes may be made in the 20 details of construction thereof without in any way departing from the scope of the appended claims.

What I claim is:

1. In a saw set, a body block, a setting

head pivotally mounted over said body block, said block having a setting surface under the head, the body block being provided below the head with a transverse slot and with rectangular recesses in its sides aligned with the said slot, guide arms disposed at the side of the body, square bosses on said arms extending into the recesses and a clamping bolt passed through said arms and through the slot.

2. In a saw set, a body block, a setting 35 head pivotally mounted over said body block, said block having a setting surface under the head, guide arms adjustably disposed at the side of the body, means to clamp said arms in adjusted position, and means to prevent rotation of the arms when clamped.

In testimony whereof, I affix my signature, in the presence of two witnesses.

FRANK W. BROWN.

Witnesses:

IDA M. WALL,
W. ERNEST LITTLE.
